UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

DESIGN FOR A TENSION-PULLEY HOLDER.

43,581.

Specification for Design.

Patented Feb. 18, 1913.

Application filed July 26, 1912. Serial No. 711,736. Term of patent 14 years.

To all whom it may concern:

Be it known that I, ALONZO E. RHOADES, a citizen of the United States, and resident of Hopedale, in the county of Worcester and State of Massachusetts, have invented a new, original, and ornamental Design for a Tension-Pulley Holder, of which the following is a specification, reference being had to the accompanying drawing, forming part thereof.

The drawing is a perspective view of a tension pulley holder, showing my new design.

I claim:

The ornamental design for a tension pulley holder, as shown.

ALONZO E. RHOADES.
